HYDRAULIC LOCK DRY PIPE VALVE WITH
WELL TESTING AND WELL FLOWING AP-
PARATUS

Arthur E. Johnson, Taft, Calif.

Application August 31, 1937, Serial No. 161,792

20 Claims.

(Cl. 166—1)

I gave my invention the above title as an hydraulic lock valve is an important feature in maintaining a dry or empty stem of drill or other pipe used in deep well drilling such as oil drilling. 5 Where it is desired to use dry or empty drill pipe in making a test of the well formation, it is necessary to have a type of valve at the bottom of the stem which prevents entrance of any of the slushing mud, used for instance in rotary well drilling prevents entrance of water or any oil in the well except the part to be tested. On account of 10 extraordinary large hydraulic pressures in deep wells it is difficult to provide a valve which may be opened from some action at the top of the well and which, when opened, will allow entrance into the drill stem of the fluid in the formation being tested. Some of these valves now used open so 15 quickly that they operate with a decided shock and on account of the rapid flow of possibly oil, water, and sand have a decided erosive action both on the stationary and movable parts of the valve. In addition, considerable difficulty has been experienced in manipulating the valves for 20 opening.

Similar troubles arise where it is desired to start, for instance an oil well flowing by inserting in the well a dry or empty oil pipe leading to the top of the well. In such cases, it is necessary to use what is sometimes termed a dry pipe valve to 25 maintain such pipe empty until it is desired to release the valve and start the flow of the oil.

By use of my hydraulic locked valve, the hydraulic lock may be opened or released and the hydraulic fluid bled out of the valve and by the 30 action of the hydrostatic pressure of the oil in the well, the valve is displaced permitting a gradual and then a free or unobstructed flow of the oil into the oil tubing extending to the top of the well.

In this application I have presented two structures and uses for my type of hydraulic lock dry pipe valve, one of which is of use in testing a well 35 formation to obtain a sample of the oil or water or any fluid mixture at the bottom of the well. The other application of my invention is for use in starting of a flowing well, for instance after a well has been tested and found satisfactory and then equipped to allow and receive the free flow of oil from the formation.

A characteristic of my hydraulic locked valve is 40 that such valve includes two valve bores or valve cylinders preferably of different diameters, the valve assembly being arranged in the body structure which may be attached by threading to the bottom of a string of drill pipe or oil tubing. In 45 the body of the valve there is a hollow space for

containing a liquid which is filled into this space at the top of the well for running in the dry pipe with its valve at the bottom.

The valve contains preferably a differential piston assembly, this having two distinct pistons 5 corresponding to the particular bore in which they slide. These pistons have suitable cup piston rings to form a liquid-tight seal with the bores or cylinders in which they operate. The fluid is maintained locked and thus locks the valve from 10 movement by means of a frangible orifice device, this having a small bore communicating with the body of the locked fluid. Such frangible device is located at the bottom of the stem of dry pipe and may preferably extend into the lower end of such 15 pipe. When the operator is ready to make his test or start a well flowing, an instrument designated in the trade as a "go-devil" or a ball may be dropped down through the drill pipe and wedging against the frangible stem breaks this at a 20 weakened section, thus exposing the small bore duct.

As the pistons are exposed to the hydraulic pressure at the bottom of the well in the fluid such as oil in the well the breaking of the frangible element and exposing the duct allows the pistons to move as a unit through the chamber containing the locked liquid, this bleeding out upwardly through the duct. On account of the tapered shape of the body of the valve leading to one or 25 the other of the bores in which the pistons operate, as the piston is displaced there is first a small cross-sectional area developed for the flow of the fluid from the well and then as the piston displacement becomes greater, the entire cross-section of one of the valve bores is free for the 30 upward flow of the oil or other fluid from the bottom of the well.

As my hydraulically locked dry pipe valve has a 35 relatively simple application as a dry pipe starter valve for flowing wells, the characteristics of this will be first set forth.

A tubular valve body is secured as by threads to the lower end of a stem of oil tubing, this preferably has a small cylindrical bore adjacent its 40 upper end, an enlarged chamber with lateral ports leading to the open hole and a larger bore at the bottom portion. The piston assembly includes a small bore piston at the top in the smaller bore, a large bore piston in the larger bore, these being 45 connected by a substantial tubing or hollow rod. The pistons each have a passage from end to end in alignment with the hollow rod. At the lower end of the valve body assembly I provide a relatively long pipe or tube which may be of larger 50 55

bore secured to the lower end of the valve assembly and provided at the bottom with an opening having a closure plug. The upper end of the small upper piston is provided with the frangible duct bar. The duct as above mentioned, is of quite small cross-sectional area compared with the bore in which the pistons operate and the upper end of this projects into the dry pipe area and such a position that it may be readily broken 5 in a weakened spot or weakened line by dropping a "go-devil" or ball. The valve is locked closed by providing a shoulder against which the lower or larger piston may seat and filling the fluid pipe after removal of the bottom plug, all this being 10 15 done at the top of the well so that on replacement of the plug the valve is held in its seated position whereby on account of the cup rings there can be no leakage either past the large lower section of the piston or the small diameter upper section. 20 25 30 35 40 45 50 When the string of oil tubing is introduced into the well it will thus be seen that the locked hydraulic valve maintains the oil tubing dry or empty. When the top of the well is equipped to receive oil released for flowing, the dropping of the ball or "go-devil" breaks the frangible duct bar and as the ports in the side of the valve admit entry of oil from the well formation at a very high pressure a differential pressure is exerted on the two piston ends. Manifestly, the lower end being of larger diameter than the upper end, a downward movement of the whole piston assembly occurs, this forcing the locked fluid upwardly through the two pistons, the connecting hollow rod, and through the bleeder duct. As the upper piston is pulled downwardly through the upper bore of the valve body the well fluid flows upwardly into the oil tubing. The piston assembly is completely displaced and descends through any of the locking liquid in the locked fluid chamber of the valve. Thus, the larger lower piston end, the smaller upper end, and the connecting tubular rod, the balls, or "go-devil" used to break the frangible duct and the broken part of this duct descend by gravity below the intake ports provided for the upflow of oil from the well formation. As these do not in any manner hinder the flow of oil they are allowed to remain as long as the well is flowing and may even be left if the well may be satisfactorily pumped with the ports provided in my dry pipe starter valve assembly.

The main characteristic features of my invention as applied to a well testing apparatus include the locked hydraulic valve in a multiple valved assembly device secured to the lower end of a string or stem of drill pipe to maintain such pipe empty or dry prior to securing a sample. In this case the locked hydraulic valve is arranged to have a differential piston in a cylinder construction mounted with the large end upwardly and the small end extending downwardly. The large end however is restrained from operation by the locked hydraulic fluid which may be released by a frangible orifice device broken by a go-devil or a ball dropped through the drill pipe. This valve is hydraulically locked at the top of the well before lowering the equipment.

With my equipment a test of the formation may be made by a rat hole, that is a small bore 70 extending downwardly from the main bore of the well and separated from such main bore by a conical packer located adjacent the bottom of the multiple valve assembly or may have a packer cutting off the lower part of the main bore when 75 it is desired to test the bore itself. In lowering

the equipment of the well I employ a slide valve actuated by a sliding mandrel operative in a second or intermediate body structure below that carrying the locked hydraulic valve. In lowering the equipment the intermediate body section 5 is suspended on studs or bosses engaging in a vertical slot on the interior of the body, such studs projecting from the sliding mandrel. This holds the slide valve closed which valve has a communication through a lower hollow by-pass 10 mandrel to a perforated inlet pipe extending downwardly in the rat hole or a perforated intake device located below the packer when the device is used to test the well bore.

Then when the packer is seated thus supporting the intermediate body section by the formation, the drill pipe with the slide mandrel is lowered thereby opening the slide valve and giving a communication of the hydraulic fluid in the test part of the well to have access to the lower, 20 that is, the small piston end of the locked hydraulic valve. When everything is set to make the test of the formation a go-devil or ball is dropped through the drill pipe and this strikes the frangible orifice device, breaking this and 25 allowing bleeding upwardly of the locked hydraulic fluid. Such action releases the hydraulic pressure on the upper or large end of the differential piston, allowing the piston to be forced upwardly by the pressure of the formation fluid on the 30 small end of such differential piston.

A characteristic of this small end of the differential piston resides in its forming a control for the velocity of flow of the formation fluid through the valve cylinder in which the small piston operates. The small piston at its lower end has tapered flutes whereby when forced upwardly by the bleeding of the locked hydraulic fluid, on the gradual upward movement of the differential piston a low velocity flow of well fluid is obtained 40 due to the small cross sectional area of the flutes and the upper part of the cylinder of the small differential piston assembly. Then as this piston travels further upwardly the cross sectional area due to the increased depth of flutes gradually 45 increases until the full area of the valve cylinder is presented for the upward flow of the hydraulic fluid to and through an annular passage surrounding the locked hydraulic fluid valve into the dry drill pipe.

A further characteristic of my invention resides in the trapping of the sample fluid in the drill pipe and developing a by-pass or equalizing pressure through a by-pass or equalizing valve between the pressure of the slushing mud or fluid 55 above the packer and the fluid formation in the well such as in a rat hole below the packer or the lower end of the well bore below the packer. In such action the drill pipe is slightly lifted to operate the slide valve to a closed position and a 60 partial rotation is given causing the bosses or studs on the slide mandrel to follow upwardly inclined diagonal grooves in the interior of the intermediate body section connecting with the first or main vertical grooves. Such studs in 65 making the test are located in the open slide valve port position slightly below the inclined grooves. A further upward movement of the mandrel with its studs or bosses brings these to 70 approximately the top of secondary vertical grooves on the interior of the intermediate body section and brings a pulling collar on the sliding mandrel in contact with a pulling shoulder on the intermediate body section. The slide valve 75

in this position is closed thus locking any well formation fluid in the drill pipe.

This immediate action releases by-pass or equalizing valves for opening. Such valves located in a lower body section are preferably of a ball and plug type maintained closed by the balls engaging a hollow by-pass mandrel secured to the lower end of the main sliding mandrel and in communication with the formation to be tested, the formation fluid having passed upwardly through this mandrel and through the sliding valve. As soon as these by-pass valves are released the pressure of the slushing mud or fluid in the well above the packer forces such valves open and flows downwardly into the formation below the packer, that is, into the rat hole or the lower part of the well bore as such is being tested. This permits ready release of the packer from the well bore and raising of the drill string with its sample and a multiple valve assembly to the top of the well.

A further characteristic feature of my invention includes a circulation valve by which the slushing mud or fluid used in hydraulic drilling may be pumped downwardly below the released packer if for any reason it is necessary to do so to save the well. Of course in this action the sample is lost but the circulation of slushing fluid may be started and maintained. Such circulation valve preferably includes a rubber plug with a ball located in a reduced cylindrical section at the top of the hollow by-pass mandrel at its connection to the main mandrel, there being a bore communicating with the annular space surrounding the locked hydraulic fluid valve to the circulation valve. On the circulation fluid being pumped downwardly through the drill pipe this plug with the ball is forced downwardly through the hollow by-pass mandrel into the perforated formation fluid intake located either in the rat-hole or in the main bore under test. Thus the hydraulic slushing fluid may be re-circulated in the well. A further detail feature of my invention is that such re-circulation may be started without releasing the by-pass valves should this be necessary as the fluid pumped below the packer equalizes with the fluid above the packer so that the whole equipment at the proper time may be removed from the well, that is, after the circulation has been properly established. Then by re-setting the hydraulic fluid locked valve and installing a replacement fragile orifice device, a second test may be made.

It will thus be seen that with my invention employing the hydraulically locked valve that I provide for those occasions in well drilling for running a string of empty or dry pipe such as tubing or drill pipe into the drilled hole and maintaining this dry or empty until the occasion arises to permit flow of fluid from the well into such dry tubing or pipe. In testing for production in an oil well the drilling stem or string of drill pipe is used temporarily as oil tubing from the bottom of the well to the top of the hole. This pipe is run into the well hole dry by being equipped with my hydraulic locked valve and the testing apparatus attached to the extreme lower end. With this apparatus a sample of the gas, oil or water content of the bottom of the drilled hole is taken from below the static column of drilling fluid which is contained in the bore hole. This sample of formation matter or liquid either flows up to the top of the hole if the formation pressure is sufficient or that which does enter the test string of piping is trapped in the empty

drill pipe and removed for analysis. Such sample therefore determines the completeness of the well at the particular depth and shows whether or not it is desirable to drill deeper.

In the case of starting a well to flow after the drilling process is completed and production is certain, my hydraulic locked dry pipe valve maintains a dry or empty string of oil tubing which is run into the bore hole for permanent installation through which the oil and gas may flow to the top of the well. By opening the hydraulic locked valve which is attached to the lower end of the tubing, the well may be started to flow provided there is sufficient formation pressure to force the fluid to the top of the well. Should this formation pressure not be sufficient to develop a flowing well such well could be pumped in the ordinary manner. It will be noted that my dry pipe valve permanently attached to the bottom of the oil tubing causes no restriction in the continued flowing of the oil and gas production after this is established.

Practical applications of my invention are illustrated in the accompanying drawings, in which:

Fig. 1 is a vertical section showing a starter valve for flowing wells with my hydraulic lock valve, the sealing valve body and the locking fluid body being shown in vertical section and the internal parts of the differential piston assembly in elevation. In this figure the hydraulically locked valve is shown in closed position.

Fig. 2 is a section similar to Fig. 1 showing the hydraulic locked valve and the sealing valve in the full open position.

Fig. 3 is an enlarged section of part of the assembly of Fig. 1 showing the differential pistons and the detail construction of the sealing valve portion of my invention.

Fig. 4 relates to a well testing device utilizing my hydraulic lock valve. This figure is a vertical section through a portion of a well bore, rat-hole and packet seat with a portion of a stem of drill pipe and the various valve body sections shown in elevation.

Fig. 5 is a vertical section showing the upper body section with the hydraulic locked valve concentric therewith, such valve being illustrated in its closed position. This also includes the portion of the dry pipe valve.

Fig. 6 is a continuing lower section from that of Fig. 5 showing the intermediate body section with the slide valve and the lower body section with the by-pass or equalizing valves, and the re-circulation valve, all of these valves being illustrated in their closed position.

Fig. 7 is a partial interior elevation of a portion of the intermediate body section to illustrate vertical and inclined internal grooves.

Fig. 8 is a transverse section on the line 8—8 of Fig. 6 in the direction of the arrows.

Fig. 9 is a transverse section on the line 9—9 of Fig. 6 in the direction of the arrows.

Fig. 10 is a section on the line 10—10 of Fig. 6 in the direction of the arrows.

Fig. 11 is a section similar to Fig. 5 showing the hydraulic lock valve in its full open position thereby opening the dry pipe valve.

Fig. 12 is a section similar to a portion of Fig. 6 showing the slide valve in its open position for obtaining a sample of fluid from the well formation.

My invention as applied to a starter valve as illustrated in Fig. 3 shows the lower end of a string of oil tubing 11 which may be of the usual character. Threaded to the lower end of this string is 75

the sealing valve body 12. This is illustrated as connected to the tubing stem by an internal threaded box 13 and at the bottom it has an externally threaded pin 14 which engages the internal threads of a box 15 at the upper end of the locking fluid body 10. This latter is shown as internally threaded at the bottom 17 to which is connected a fluid chamber cylinder 18, this latter having external threads at the top and 10 may be quite thin. Such cylinder has a closed base 19 with a filler opening 20 closed by a plug 21.

The characteristics of the locked hydraulic valve, designated by the assembly numeral 25 include the internal large cylinder 26 forming the interior of the locking fluid body 16, this having a downwardly facing shoulder 27 at the top and a relatively large opening 28, above the shoulder. Such shoulder is illustrated as adjacent the upper end of this locking fluid body. The sealing valve body 12 has an internal cylinder 29 of less cross sectional area than the opening 28. A relatively large cylinder 30 in the valve sealing body has a plurality of production ports 31, these being in the form of vertical slots. A coned taper 32 connects the upper end of the cylinder 30 with the lower end of the piston cylinder 29 and above this piston cylinder there is a diverging cone 33. A tubular piston rod 35 has an upper tubular piston 36 secured thereto by the threaded connection 37 (note Fig. 3) and at the lower end there is the large tubular piston 38 secured to the rod by a threaded connection at 39. The upper piston has a reduced cylindrical neck 40 on which is mounted a series of cup leathers 41 separated by ring followers 42. In the illustration 3 cup leathers are shown facing downwardly. A nut 43 threaded on the upper end of the neck retains the followers and cup leathers in position. The lower piston also has a reduced neck 44 with an upper cup leather 45 facing upwardly and a series of lower cup leathers 46 facing downwardly, these being separated by follower rings 47 and the assembly held in place by a nut 48 threaded on the lower end of the neck 44.

The frangible orifice device designated by the assembly numeral 55 has an upwardly extending bar structure 56 (note Fig. 3) with a small bore duct or orifice member 57 extending upwardly, there being an internal cone 59 leading to the base or bottom 60. This is seated on the bottom of a recess 61 in the neck of the upper piston, the assembly being held in place by a gland nut 62, there being packing 63 between the nut and base 60. An annular groove 64 or other weakening structure is formed in the rod below the top of the orifice duct 57. It is preferable that the rod extend upwardly a short distance within the lower end of the lowermost stand of the oil tubing.

60 In the manner of operation of my invention in assembling at the top of the well, liquid of a suitable type such as water is filled in the fluid sealed space **70**. This is the space in the locking fluid body **16** and the fluid chamber cylinder **18**. When this is filled so that the piston assembly **25** is thrust upwardly the plug **21** is inserted. This assures that the upper end of the lower piston bears against the seat **27**. The cup leathers facing downwardly on the lower piston assure that there will be no leakage of the locked fluid upwardly into the inlet annular chamber **71** in the sealing valve body **12** immediately inside of the ports **31** and surrounding a piston rod **35**. When in this position the upper piston **36** is located in the piston cylinder **29**, the upper end with the nut **43**

and the gland nut 62 extending upwardly in the widening cone 33 and the lower end preferably extending downwardly within the contracting cone 32.

With the pistons in this position and the frangible orifice device 55 in place the assembly with the string of oil tubing is lowered into the well in the ordinary manner. The frangible device may be made of such material as Bakelite, glass, hard rubber or the like. The assembly is lowered through any residual liquid or slushing mud in the well. When at the proper depth the tubing is secured at the top, that is, adjacent the derrick floor and suitable equipment is attached to the top of the string of tubing to control the upward flow of oil when this takes place. By this construction and procedure, the tubing is what is termed dry, that is, empty, containing no oil or no liquid and although the liquid and oil in the well may enter the ports 31 it is absolutely blocked from upward flow no matter what the pressure by the upper piston 36. Manifestly this piston assembly is locked by the fluid in the chamber 10. The downwardly facing cup leathers on the upper piston prevent upward seepage of liquid no matter what the pressure in the well.

When it is desired to start the well flowing, a ball or go-devil indicated by the numeral 72 in Fig. 2 is dropped downwardly through the dry or empty oil tubing. This ball is of slightly greater 30 diameter than the radial distance from the outside of the rod portion 56 and the inside of the oil tubing but is of a less diameter than the piston cylinder 29 and the opening 28. The ball therefore strikes the rod 56 and breaks this at the 35 weakened line 64, thus exposing the opened end of the duct orifice 57.

A differential pressure is developed on the upper and lower pistons due to the oil or other liquid in the well which has entered the ports 31 and filled the annular space 11. This bears downwardly on the upper end of the lower piston and the lower end of the upper piston but as the lower piston is larger in diameter and has a larger area exposed through the opening 28, there is a greater total pressure downwardly. This therefore forces the piston assembly downwardly in the locking fluid body 16 and displaces the fluid 10 which flows upwardly through the tubular lower piston 38, the tubular piston rod 35, the tubular upper piston 36 and through the contracting open cone 59 and the open orifice duct 51. This gives a relatively slow discharge allowing the piston assembly to move downwardly slowly. The internal cylinder 30 is larger than the upper piston 36 so that there is always room for flow of oil upwardly around this upward piston when it descends a sufficient distance to develop an annular opening surrounding the nuts 43 and the gland nut 62. The hydraulic pressure in the well together with the action of gravity causes the piston assembly to still move downwardly until the complete piston cylinder 29 is open for the upward flow of the oil from the well. The piston assembly with the ball 72 and the broken piece from the upper end of the bar 51 drops downwardly into the fluid chamber cylinder 18 which brings the upper end of the upper piston a considerable distance below the production ports 31, hence the valve assembly has no interference with the production of oil. The various parts of the equipment which thus drop downwardly and rest on the bottom 19 are left in the well as they perform no adverse function in the free flow of flowing a well and under some cir- 75

cumstances even if the oil requires pumping in the oil tube these may still be left in the well until occasion arises to remove the oil tubing.

It will thus be seen that by my invention I 5 employ a locking fluid for locking a dry tubing valve in its closed position. The particular valve which shuts off the production may be considered as the upper piston, that when the frangible device is broken the locked fluid is released permitting 10 opening of the dry pipe valve and thus starting the production of oil in a flowing well which may continue indefinitely.

It is believed obvious that the differential piston action for the hydraulically locked valve may 15 be obtained by, for instance, having the upper and lower pistons of the same size operating in suitable cylinders and with a compression spring seating on the lower cylinder and on a shoulder extending inwardly on the large cylinder 30. With this construction the pressure of the spring 20 will start and continue the downward movement of the piston assembly bleeding the hydraulically locked liquid through the orifice until the piston assembly is free to drop by gravity.

My invention incorporated with a well testing equipment is substantially as follows as illustrated in Figs. 4 through 12 inclusive. In this case referring to Fig. 4 the lower portion of a well bore is indicated by the numeral 90. The drawings illustrate a bottom portion in which no casing has been set however it will be understood the casing may be in this portion of the bore if desired. A rat-hole 91 extends downwardly into the oil bearing formation 92 from 35 which a sample is to be taken. A reamed seat 93 is made in a standard manner between the large bore of the well hole and the small bore of the rat-hole. This is to form a seat for a tapered packer when testing the formation by a rat-hole. It will be understood that if a full bore extends 40 downwardly that the lower portion of this may be made by using an expanding packer of a standard type which seals off the upper portion of the well above the packer. Of course in both types of testing it is presumed that there may 45 be oil in the rat-hole and the bottom portion of the main bore or these may be filled with a slushing fluid or mixture of the slushing fluid and oil. In my invention a lower portion of a string of 50 drill pipe is indicated by the numeral 100 to which is attached an upper cylindrical body section 101 (note particularly Figs. 5 and 11). This is illustrated as having a tapered threaded box 102 adjacent the upper end for connection by a tool joint 103 or other device to the lower part of the 55 drill string. A contracted opening 104 is immediately below the box. An outwardly flared cone 105 leads to a large cylindrical section 106 of this upper body section, this terminating in a contracting cone 107 below which there is a threaded connection 108 to an upper or first intermediate body section designated by the 60 numeral 110 (note particularly Figs. 5 and 11).

This section below the threads has a relatively 65 large cylindrical bore 111 with an annular transverse shoulder 112, the lower end of the upper body section being indicated by the numeral 113 forming an opposing shoulder with the shoulder 112. A cylindrical bore 114 extends downwardly 70 from the shoulder 112 and is preferably at least of the same internal diameter as the lower threaded portion of the upper body section. An annular shoulder 115 terminates the cylindrical section 114 and below this there is an internally 75 threaded section 116 and a cylindrical bore 117.

This is illustrated as having internal threads 118 at its lower end.

A sliding mandrel designated by the assembly numeral 125 (note particularly Figs. 5, 6, 11 and 12) has an upper external thread 126 connecting 5 with the upper intermediate body section 110. The mandrel has an outside cylindrical surface 127 and has a large bore 128 at its upper part contracted to a smaller bore 129. At the bottom of the mandrel there is a screw threaded recess 10 130 with a reduced seat portion 131 to which is fitted a hollow by-pass mandrel designated by the assembly numeral 135. This mandrel seats 15 against a seating ring 136 in the seat portion 131 of the recess and is connected to the threads at 15 130. Internally this hollow by-pass mandrel has a cylindrical valve seat section 137 and a larger bore section 138 extending therebelow and through this section there are a plurality of flow ports 139 for the liquid sample to be obtained 20 from the well. The by-pass mandrel is indicated as terminating at 140. This latter mandrel is thus interconnected to the upper or main mandrel and has an up and down movement relative to the other parts of the apparatus with such 25 mandrel.

Slidably mounted on the main mandrel 125 there is the second or lower intermediate body section designated by the assembly numeral 150 (note particularly Figs. 6 and 12). This body 30 section is cylindrical on the outside and at the top has a packing bore 151 with internal threads 152 thereabove, a packing 153 for the sliding mandrel 125 is fitted in the lower portion of the bore 151 and retained in place by a gland nut 35 154 which has a depending threaded section 155 engaging the threads 152 and held in place by a lock ring 156 threaded on the threaded portion of the gland and jammed against the upper end of the second body section 150. This second body 40 section terminates at the bottom at 157 and is illustrated as being internally threaded.

To this there is connected the lower body section 170, this having a threaded connection at 45 171 to the lower end of the lower or second intermediate body. The upper end 172 forms a shoulder to seat weight on the packer as described hereinunder. This lower body section has an internal cylinder 173 forming a sliding fit with the lower end portion of the main mandrel 125. 50 A reduced cone section 174 leads to a cylindrical bore 175 in which the lower portion of the by-pass mandrel 135 has a sliding fit.

A sub designated by the assembly numeral 180 (note Figs. 4 and 6) is connected by any suitable 55 type of threaded joint 181 to the lower end of the lower body section 170. The bore 175 extends into this sub and the sub also has a perforation extending therethrough. On the sub is the tapered packer 182 and below the packer 60 a small diameter intake perforated tube 183. The tapered packer is designed to seat on the seat 93 connecting the main well bore 90 and the rat-hole bore 91. It is to be understood that any suitable type of packer might be utilized and 65 if the sample is to be taken from the lower portion of the main well bore, that an expanding type of packer will be used. These are quite well known in the art as is also the structures and manner of expanding. The perforated tube 70 183 is for the purpose of permitting the upward flow of the liquid from the portion of the formation to be tested.

My hydraulically locked valve is designated by the assembly numeral 200 (note particularly 75

Figs. 5 and 11). This employs a confining fluid cylinder 201 having an enlarged collar 202 at the bottom which fits in the cylindrical section 111 of the upper or first intermediate body section 110. It is seated on the shoulder 112 and held tightly in place by the lower end 113 of the upper body section through the medium of a resilient washer if necessary. This construction holds the cylinder 201 vertical and concentric with the main body section 101. There are a plurality of preferably circular ports 203 in the collar 202 communicating from the space 204 to the hollow space 205 within the cylinder 201.

A valve plug 210 is fitted to the upper end of the cylinder 201. This has a valve seat 211, a perforated cage 212 and a ball 213 to engage on the seat limited as to its upward movement by the perforated cage plate 212. An externally threaded neck 214 extends upwardly from the valve plug and is cylindrical on its inside surface. This forms a mounting for the frangible orifice duct device 220. Such device has a base section 221 seating on the cage plate 212. It has an upwardly extending bar section 222 with compressible packing rings 223 retained in place by a gland nut 224, this having internal threads and being threaded on the external threads of the neck 214. The lower surface of the gland nut and of the valve plug 210 contact as indicated at 225. The orifice element has an internal open cone 226 extending upwardly from its lower end from which there is a central orifice duct 227. This extends above the annular groove 228 or other device forming a weakening section. A tubular sleeve 230 has a threaded connection to the outside of the gland nut and extends upwardly preferably above the top of the frangible orifice bar 222, having an internal bevel 231 at the top. This leaves a space 232 between the top of the sleeve and the contracted opening 104 adjacent the top of the upper body section. The internal opening in the sleeve 230 should be approximately equal to that of the opening 104 to direct the downward path of a go-devil as hereinunder described.

The hydraulic locked valve employs a dry stem sealing valve cylinder designated by the assembly numeral 240 (note particularly Figs. 5 and 11). This has an upper shoulder section 241 bearing on the shoulder 115 of the upper intermediate body section 110 and has external threads engaging the threads 116. The outside lower cylindrical part 242 is preferably slightly smaller in diameter than the inside cylinder 111. Wrench grip notches 243 provide for threading this valve cylinder in place. Such cylinder has an internal cylindrical surface 244 with a conical flare 245 at the bottom and a conical piston engaging shoulder 246 at the top.

The piston assembly designated by the assembly numeral 250 has a piston rod section 251 cylindrical on its outside surface and provided at its upper end with a relatively large diameter piston 252. This is illustrated as having a stem 253 (note Fig. 5) with a plurality of cup leathers 254 separated by follower rings 255, these being held in place by a nut 255' at the top of the stem. These cup leathers it will be noted are faced upwardly to resist leakage of the locked fluid in the space 256 inside of the cylinder 201 below the valve plug 210 and the piston. At the lower end of the cylindrical part of the piston rod 251 there is a converging coned seating plug 257 preferably formed integral with the rod section and below this is a small diameter piston

258. This employs a stem 259 with a plurality of cup leathers 260 thereon separated by follower rings 261. The assembly is held in place by a displacement mandrel 265 threaded on the lower end of the stem 259. This is preferably locked in place by a set screw and has a plurality of tapering flutes 266, these flutes being of greater depth at the lower end than at the upper end of such mandrel for a purpose hereinunder described.

The sample shut off retaining valve designated by the assembly numeral 275 is illustrated particularly in Figs. 6, 8, 9 and 12. One side of the sliding mandrel 125 adjacent its lower portion is provided with a longitudinal groove 276. This has a flat base surface 277 parallel to the bore 129 and has two side edges 278. These terminate at the top in a transverse shoulder 279 at right angles to the axis of the mandrel and at the bottom in the upwardly inclined shoulder 280. Below this shoulder the mandrel has a flat side 280' to provide upward flow of the sample. Intermediate the length of this groove there is a port 281 leading to the bore 129. This port is shown as located within the area of an enlarged collar 282 on the mandrel which operates in an enlarged internal diameter bowl 283 of the second or lower intermediate body section 150. The upper part of this collar has a bevel 284 adapted to engage the complementary bevel 285 pulling shoulder at the top of the bowl. The lower annular edge 286 is transverse to engage the seating shoulder or end 172 at the upper end of the lower body section 170. A sliding valve block 290 (note particularly Figs. 6, 8, 9 and 12) has an outer convex periphery 291 to have a snug fit in the bore of the bowl 283. The opposite vertical sides 292 are vertical and parallel to fit in the sides 278 of the slot 276 of the mandrel and the block is provided with a flat base 293 to engage the flat inner base surface 277 of this slot 276. The upper edge of the block is transverse as indicated at 294 and has a slight corner bevel 295 to fit against the bevel 285. The lower edge has a transverse outer portion 296 fitting on the shoulder 172 of the lower body section 170 and from this there is a slight bevel 297 to conform to the upwardly inclined shoulder 280. The block is provided with a liquid flow duct 288 and a port 289 which is brought into and out of registry with the port 281 of the mandrel 125 when this mandrel moves up and down. It will be understood that the block 290 is held practically stationary but there is a slight clearance at each end providing for a slight up and down movement to take care of any inaccuracy of fit. In order to tightly seat the valve block against the mandrel to prevent leakage therewith, the block is provided with one or more recesses 298 in which are fitted compression springs 299 bearing on the base of a recess 283 and against the cylindrical surface of the bowl 283.

The slot and stud assembly 310 for regulating the position of the sample shutoff valve 275 employs a first or a long vertical slot 311 in the second or lower intermediate body section 150 (note particularly Fig. 7). This extends vertically upwardly from the upper end of the bore of the bowl 283 and terminates with rounded end 312 at the top. An upwardly sloping slot 313 extends laterally from the vertical slot 311, the upper edge of this slot being positioned below the rounded upper end 312 and extending upwardly from this slot 313 there is a second or a shorter vertical slot 314 also terminating in an upper

rounded end 315. Each of these sets of slots is located preferably diametrically opposite in the second intermediate body section, that is, the first vertical slots 311 are diametrically opposite, the inclined slots 313 also opposite and the second vertical slots 314 are opposite one to the other. The mandrel is provided with two diametrically opposite substantial studs 316 to operate in these slots, the manner of operation and functioning 10 being detailed hereinunder.

The by-pass or equalizer valve assembly 325 (note particularly Fig. 6) employs one or more transverse perforations 326 in the thick lower portion of the lower body section 170 and leading 15 to the cylindrical bore 175. In each of these bores there is a ball 327 adapted to contact the outside surface of the by-pass mandrel 135 adjacent its lower end and immediately outside of each ball there is a rubber plug 328. The plugs 20 are seated by a tubular nipple 329 threaded in the outer threaded end of the perforation 326. It is manifest that as many of these balls and valve assemblies will be utilized as are necessary to give the desired by-pass or equalizing flow downwardly 25 below the packer as are necessary. These valves are held in their inactive or closed position by the lower portion of the by-pass mandrel 135 engaging the balls and preventing the balls and plugs being forced inwardly.

30 The re-circulating valve designated by the assembly numeral 335 includes a ball 336 seated upwardly against the seating ring 136 which is located in the recess 130 extending upwardly from the bottom of the sliding mandrel 125. The ball 35 has a sliding fit in the cylindrical valve seat section 137 of the by-pass mandrel 135. Below the ball there is a rubber plug 337 which with the ball is inserted upwardly through the open lower end of the by-pass mandrel 135 and has sufficient 40 friction to prevent the rubber plug and the ball being forced outwardly until this is accomplished by a downward hydraulic pressure by pumping slushing fluid or the like.

The manner of operation and functioning of 45 my well testing apparatus is substantially as follows: The various sections are assembled at the top of the well. For instance, the valve cylinder 240 is inserted in the upper intermediate body section 110 prior to locating the confining fluid cylinder 201, the piston assembly 250 having the 50 small piston end inserted in the cylinder 240, the fluid chamber 256 may be filled with water or other fluid before connecting the frangible orifice duct device 220, the upper body section 101 is then connected to the upper intermediate section 110. The second or lower intermediate body section 55 150 is fitted over the sliding mandrel 125, the slide valve 275 is assembled and the studs 316 on the mandrel are guided into the first vertical slots 311 seating against the upper end 312. The by-pass mandrel 135 with the re-circulating valve assembly 335 is fitted to the mandrel, the remaining lower intermediate body section 170 is then assembled with the by-pass valves 325 and a suitable type of sub indicated at 180 with a suitable packer and perforated intake pipe which may have the function of an anchor completes the installation. As above mentioned if the sample is to be taken 60 from a rat-hole, a cone packer such as 182 is utilized but if the sample is to be from the full bore well hole a suitable type of expanding packer is utilized, these being well known in the art. After assembly of my equipment it is lowered into the well by connecting the various stands of drill pipe. 65

70 In the procedure of lowering, all of the parts be-

low the upper intermediate body section 110 are suspended from the studs 316 on the mandrel engaging the upper end 312 of the first vertical slots 311. This positions the sample shut off valve assembly 275 in a closed position, that is, the port 281 on the mandrel and the port 289 in the valve block are out of registry. Thus the hydraulic pressure in the well is shut off from the bore 129 of the mandrel above the recirculating ball valve 336. However any possible leakage past this is 10 immaterial as the pistons of the piston assembly 250 are locked in the closed position by the fluid locked in the chamber 256.

When the packer is seated a slight downward movement of the mandrel in reference to the lower body section 170 and the lower intermediate body section 150 brings the lower annular edge 286 on the collar 282 of the mandrel in contact with the shoulder 172 on the upper end of the lower intermediate body section 170. Thus sufficient 20 weight may be placed on the packer to secure a tight seal and to close off the rat-hole where a tapered packer is used from the main well bore. Likewise when a test is being made of the full well bore the packer makes a hydraulic seal between 25 the slushing fluid above the packer and the fluid in the well below the packer. This action of seating the packer and lowering the sliding mandrel in reference to the parts which are held stationary aligns the ports 281 and 289, thus developing a 30 hydraulic pressure in the upper or large bore 128 of the sliding mandrel immediately below the valve cylinder 240. This cylinder is closed by the lower or small piston 258 which as above mentioned, has the cup leathers facing downwardly 35 to prevent upward leak of the fluid of the sample being tested. Such fluid develops a pressure through the perforated pipe 183 from the rat-hole or the part of the well to be tested. When everything is ready to make the test a go-devil indicated at 350 (Fig. 11) which may preferably be in the form of a bar, is dropped down through the dry or empty drill pipe. This is guided by the drill pipe and the opening 104 at the upper end of the upper body section and also by the tubular sleeve 230 so that it wedges between such sleeve and the frangible orifice bar 222, thus causing a breaking of this bar at the weakened section 228. (note Fig. 11). Therefore the lock confining the lock fluid in the chamber 256 is released and due 40 to the very high hydraulic pressure pressing upwardly on the small piston end 258, the whole piston assembly is forced upwardly causing the large diameter piston 252 at the top which has the cups facing upwardly to be forced in an upward direction in the cylinder 201. This action develops an upward flow of the confined or locked fluid through the small orifice 221, this being a 45 bleeder. Such action unseats the ball valve 213. 50

The graduated flow of the sample under test 55 which is usually at a very high pressure compared with the atmospheric pressure in the dry or empty drill pipe is developed as follows: As the piston assembly 250 is forced upwardly there is a full and complete seal in the valve cylinder 240 until 60 the cup leathers pass above the upper end of the cylindrical section 244. This then brings the upper end of the flutes 266 in the further upward movement of the piston assembly, into the cone 246. Such action allows first a somewhat slow 65 flow of the sample from the well and as the piston assembly is still forced higher, the larger or bottom end of the flutes on the displacement mandrel 265 allow an increased flow. Then as the piston assembly is forced up still further, the 70 75

small piston entirely clears the cylinder 240. The sample being taken flows upwardly through the series of ports 203 in the collar 202 and passes upwardly in the annular space between the cylinder 201 and the inside of the upper body section 101. The piston assembly 250 is driven upwardly by the pressure into the upper part of the cylinder 201 somewhat as illustrated in Fig. 11. The flow of the sample follows substantially the direction of the arrows indicated as passing outwardly through the perforations 139 by the numeral 351 past the flat side 280' at the lower end of the sliding mandrel as indicated at 352, through the aligned ports of the slide valve at 353, upwardly 15 through the mandrel as indicated at 354, through the cylinder 244 at 355 and upwardly following the arrows 356 and 357 (note Figs. 11 and 12). After allowing the upward flow of the sample to be obtained for the desired length of time, it is necessary to close the sample retaining valve 275. This is done by slightly lifting the string of drill pipe with the upper body section and the mandrel. This disengages the shoulder 286 on the collar 282 from its seat 172 and brings the studs 316 into alignment with the lower end of the inclined slots 313. Such studs have been slightly below this slot as indicated in Fig. 12 during the flow of the sample and the alignments of the ports 281 and 289. Then a slight rotational turn 20 of the drill string which causes a slight rotation of the mandrel guides the studs 316 upwardly in the inclined slots 313 into the second vertical slot 314 when a vertical lift on the drill pipe brings these studs upwardly in these slots 314. Such action dis-aligns the ports 281 and 289 shutting off the sample retaining valve. In the rotation of the mandrel the block 290 of course rotates with the mandrel. The drill pipe is lifted until the pulling shoulder 285 in the lower intermediate body section 150 is engaged by the inclined shoulder or bevel 284 of the collar 282 on the mandrel. When so engaged there is a clearance between the studs 316 and the end 315 of the slots 314. Hence the entire lifting pull is taken between the complementary shoulders 284 and 285.

However, before unseating the packer and lifting the sample it is necessary to equalize the pressure in the well above and below the packer. During the taking of the sample the by-pass valves 325 have been retained in their closed position on account of the balls 327 engaging the lower portion of the tubular by-pass mandrel 135. These valves are held in this position manifestly when the assembly is being run in the well and while the sample is being taken. However when the studs 316 are located in the slots 314 the mandrel with the by-pass mandrel 135 is raised so that the lower end 140 is brought above the valves 325. Then the pressure of the slushing fluid and any other fluid in the well above the packer forces the plugs 328 with the balls inwardly so that these may drop downwardly into the perforated intake pipe 183 or an anchor where such is used. This gives a free passage for the fluid above the packer to equalize the pressure below the packer and maintains an open passage so that the assembly with the packer may be elevated to the top of the well, stand by stand of the drill pipe being removed in this procedure. Thus as the sample taken from the well is trapped in the formerly dry drill pipe, an accurate sample may be taken of the flow of oil and other liquid from the well, that is, from the portion under test.

The function of the re-circulating valve 335 is as follows: This valve is only intended to come

into operation when through some reason or other it is found necessary to re-start the circulation of the slushing fluid. This may be necessary to give sufficient pressure to seal off the well or to start the circulation to prevent so-called freezing of the equipment in the well. After a sample has been taken, this of course necessitates losing the sample. Thus for instance, presuming a sample has been taken and everything is ready to lift the equipment by the complementary shoulders 284 and 285 engaging, then if the drill pipe above the sample taken is filled with slushing fluid and this is pumped downwardly under the high pressure usually developed, the pressure of the fluid in the small bore 129 in the mandrel forces the plug 337 with the ball 336 downwardly completely through the by-pass mandrel 135, this plug with the ball descending into the perforated intake tube 183 or into an anchor where such is used, or at any rate, the plug is driven out of the way so that the slushing fluid pumped downwardly through the drill string may pass out through the perforated tube 183. After the circulation is properly established, the assembly may be elevated to the top of the well, the hydraulic locked valve reset and the dry drill pipe again lowered into the well to make another test.

It is sometimes desirable to have a positive high pressure on the hydraulically locked fluid in the space 256. For this purpose a valve assembly 350 may be installed in the confining fluid cylinder 201 and after attachment of the frangible duct device 200, fluid may be forced in under pressure with an instrument similar to a grease gun. This causes a positive and forcible seating of the tapered plug portion 257 of the piston rod section 251 against the cone shaped shoulder 246 at the top of the valve cylinder 240. These may be provided with surfaces sufficiently accurately made to develop a closed seal independent of the packing cups.

In the construction of Figs. 1, 2 and 3 relating to the hydraulically locked starter valve, if desired, I may have the sealed fluid 70 under an initial high pressure in which case a pressure feed valve assembly designated 360 may be incorporated in the plug 21 or other part of the device so that after the space inside of the body 16 is filled with liquid this may be brought under pressure by an instrument similar to a grease gun. Such action exerts a considerable internal pressure on the liquid 70 and forces the piston assembly upwardly so that the upper end of the lower piston 38 has a tight seat and if desired, seal, against the downwardly facing shoulder 27 at the upper part of the body 16.

I wish to emphasize the important function of the action of tapered flutes 266 in the displacement mandrel 265 in reference to the valve cylinder 240. When the piston assembly is forced upwardly and the upper end of the flutes are positioned slightly above the cylindrical section of the valve cylinder 240, on account of the small cross sectional area only a small amount of the fluid from the well which is under high pressure may flow upwardly. Then as the piston is further raised and the tapering flutes give a larger cross sectional area the flow of the well fluid becomes more rapid but the increase of velocity is at a regular increment until the piston assembly is removed entirely out of the valve cylinder 240 when the full cross sectional area of such cylinder comes into operation for the upward flow of the well fluid. This, which might be termed delayed

action, reduces the scouring due to sand or the like contained in the fluid from the well.

Various changes may be made in the details of the construction without departing from the spirit or scope of the invention as defined by the appended claims.

I claim:

1. In a well tool, a hollow structure having a chamber for a first fluid, a movable valve structure and a sealing means, a structure having a communication with the well formation whereby pressure of a second fluid may be exerted on the valve, the sealing means and the said valve locking the first fluid in the chamber and thereby restraining the valve from movement, the said sealing means having a construction for unsealing or opening from a distance remote from the valve, means for bleeding the locked fluid from the chamber due to a differential pressure on the valve between the pressure in the chamber and the pressure in the formation and means operative after discharge of a substantially predetermined amount of the hydraulic fluid flowing the second fluid from the well formation.
2. In a well tool, the combination of a hollow structure adapted for immersion in a fluid in a well, such structure having a hollow chamber for a locked second fluid, a frangible sealing means forming a closure for one part of the chamber and a movable valve means forming a closure for the other part of the chamber whereby when the chamber is filled with fluid, such fluid is locked from out-flow by the sealing means and the valve means, the frangible sealing means being adapted to be broken when desired, there being a bleeding outlet from the said chamber, means forming a fluid communication between the first fluid in the well and the valve means whereby a differential pressure between the well fluid and the locked fluid causes a bleeding of such locked fluid and a movement of the valve means, the said structure being provided with a passage for the flow of the well fluid after draining of a predetermined amount of the locked fluid by the movement of the valve means.
3. In a well tool, the combination of a tubular structure adapted for lowering into a well and forming a passage from a desired depth to the top of the well, a hydraulic locked valve assembly connected to the lower end of said structure, said assembly including means forming a hollow chamber, a frangible sealing means with a bleeding opening communicating with said chamber, a movable valve element forming a closure for another part of said chamber whereby a first and locked fluid is retained in said chamber between the frangible sealing means and the valve element, means forming a fluid communication from a second fluid in the well to the side of the valve outside of the said chamber, the said frangible sealing means being adapted to be broken by a go-devil or the like dropped downwardly through the said tubular structure, the said bleeding opening communicating with said tubular structure whereby a differential pressure between the second and well fluid and the first and locked fluid develops a movement of the valve means to bleed a substantially predetermined amount of the locked fluid out of the said chamber and means opened by the movement of the valve for the flow of the well fluid into the said hollow structure.
4. In a well tool, the combination of a tubular structure adapted for lowering into a well and forming a passage from a desired depth to the top of the well, a hydraulic locked valve assembly connected to the lower end of said structure, said assembly including upper and lower cylinders with connected slideable valve pistons therein, the upper piston operating in the upper cylinder and the lower piston in the lower cylinder, a structure forming a chamber for a first and locked fluid connected to one of said cylinders, a frangible sealing bleeder device also connected to said chamber and having a bleeder duct positioned to communicate with the tubular body structure, means forming a fluid passage for a second or well fluid to exert a pressure on at least one of the pistons, the first or locked fluid being trapped between one of the pistons and the frangible sealing means, one of said pistons preventing upward flow of the second or well fluid, the hydraulic pressure in the tubular structure being adapted to be very much less than that of the well fluid, the first or locked fluid engaging one of the pistons preventing movement of the piston assembly, the said frangible sealing means being adapted to be broken by a go-devil or the like dropped through the tubular structure and thereby opening the bleeding duct for communication with the tubular structure, the pressure of the second or well fluid on one of the pistons then being operative to move the piston assembly and force the locked fluid through the bleeding duct until the piston preventing flow upwardly of the well fluid is moved to such a position as to free the well fluid for upward flow into the said tubular structure.
5. In a well tool, a dry pipe starting valve comprising in combination a string of oil tubing, a valve body structure connected thereto at the bottom and having a small bore cylinder at an upper part, a large bore cylinder at a lower part with flow ports therebetween, means forming a closure at the lower part of the large cylinder, a piston assembly including a piston rod having a small upper piston and a large lower piston fitted respectively in the upper and lower cylinders, the pistons and the rod having a passage therethrough, the upper piston having a frangible sealing device connected thereto with a bleeding duct, said duct communicating with the passage through the pistons and the piston rod, an inter-engaging means between the piston assembly and the valve body to restrict upward movement of the piston assembly with a first or locked fluid in the large cylinder below the lower piston, such fluid being sealed by the said sealing means and forming a positive lock against movement of the piston assembly, the said frangible sealing means being adapted to be broken by a go-devil or the like dropped through the oil tubing and thus open the bleeding duct to communicate with such tubing, the said ports admitting the second or well fluid to exert a pressure on the larger and lower piston and thus force the piston assembly downwardly and causing a bleeding through the duct of the locked fluid, the upper piston thereby being retracted from the small upper cylinder and thus developing a free upward flow of the well fluid through the small upper cylinder, the whole piston assembly with the frangible means and the go-devil being adapted to drop below the said ports.
6. In a well tool, a drill pipe adapted to extend downwardly in the well to a desired depth, a well testing assembly secured thereto at the bottom, said assembly including an inflow means for well fluid from the bottom of the well, a packer engaging a wall of the well and a relatively station-

ary tubular structure positioned above the packer with means to retain the said latter structure from movement, an upper tubular part connected to the drill pipe and having a tubular mandrel vertically slideable in the lower relatively stationary structure, a sliding sample shut-off valve assembly operative between the lower structure and the sliding mandrel and forming an open connection for the fluid from the well 5 when the mandrel is in its lowermost position, a hydraulic locked valve assembly including a lower and an upper valve cylinder with a piston assembly having an upper and lower piston in each valve cylinder, a chamber forming structure 10 connected to the upper cylinder and having a frangible sealing means at the top with a bleeding duct therein to communicate with the tubular structure from the bottom of the well, there being a fluid passage through the mandrel, the 15 lower valve cylinder and upwardly outside of the upper valve cylinder and the locked fluid chamber, said chamber being adapted to contain a locked fluid between the upper piston and the frangible sealing means, said sealing means being adapted to be broken by a go-devil dropped from the top of the well to open the bleeding 20 duct, the pressure of the well fluid being adapted to develop an upward movement of the piston assembly and thus move the lower piston upwardly in its cylinder to form a flow passage 25 therethrough, after the trapping of the well fluid the tubular structure from the top of the well being adapted for upward movement and moving the mandrel upwardly to close the said sliding valve and thereby retain the sample. 30

7. In a well tool as claimed in claim 6, a bypass valve located in the relatively stationary tubular structure above the packer communicating between the inside of said structure and the outside to the well, means connected to the mandrel to retain said valve closed during the upflow 40 of a sample fluid from the well and adapted when the mandrel is raised to shut off the sample to permit opening of the by-pass valve to equalize the pressure above and below the packing. 45

8. In a well tool as claimed in claim 6, a recirculating valve assembly mounted at the lower end of the passage through the mandrel with means forming a passage to the relatively stationary tubular structure whereby after obtaining 50 a sample such sample and slushing fluid may be forced downwardly through the drill pipe, the mandrel and the relatively stationary tubular structure to the bottom of the well.

9. In a well tool having means for attachment to a string of drill pipe or the like for lowering into a well and in which a packer shuts off the portion of the well from which a sample is to be obtained, the combination of a bottom intake structure for the sample fluid, a sample fluid flow valve, a hydraulic lock valve having a chamber structure with a frangible sealing means and a bleeding duct together with a cylinder having a valve piston therein, the said chamber being adapted to be filled with a locking fluid and said fluid preventing movement of the piston valve inwardly, a second fluid flow valve operatively connected to the piston valve and subject to the pressure of the well fluid when the sample retaining valve is open, means to open the sample retaining valve for upward flow of the well fluid, the frangible sealing means being adapted to be broken by a go-devil dropped downwardly in the well, the said bleeding duct then allowing escape 70 of the locked hydraulic fluid, the pressure of the 75

well fluid being adapted to open the second flow valve and to force the piston valve to displace the locked fluid, there being a passage from the second flow valve upwardly in the well. 5

10. In a well tool, a hollow body structure having means for attachment to a drill pipe for lowering in a well and for flowing a sample of well fluid into the pipe combined with an inflow means for well fluid from the bottom of the well, a sample fluid retaining valve, means to open 10 said valve for upward flow of the well fluid, a hydraulically locked sample flow valve having a first valve means positioned to be under pressure of the well sample fluid when the sample retaining valve is open, a locked fluid structure forming 15 a chamber with a frangible sealing means having a bleeding duct and a third movable valve means, the locked fluid being trapped between the sealing means and the third valve and retaining the said second valve closed, the frangible means being 20 adapted to be broken by a go-devil dropped downwardly and striking such frangible means to thereby expose the bleeding duct whereby the pressure of the well fluid is adapted to move the second flow valve and the third valve to displace 25 the locked fluid and open the second valve for a free upward flow of the sample fluid, the sample retaining valve having means for closing same after securing a sample. 30

11. In a well tool, an upper hollow body structure having means for attachment to a drill pipe or the like for lowering in a well, a sample of well fluid being adapted to flow upwardly into the drill pipe, a lower hollow body structure, a tubular means connecting the upper and lower structures, 35 the lower structure having means for inflow of well fluid, the upper body structure having a hydraulically locked valve including a cylinder positioned in the upper body but spaced from the walls thereof, with fluid passages to said space, 40 a frangible sealing means at the upper end of the cylinder with a bleeding duct, a first piston in the lower end of the cylinder, the space in the cylinder between the piston and the sealing means forming a chamber for hydraulic locking fluid, 45 the upper body having a second cylinder with a second piston fitted therein, the two pistons being connected whereby when the fluid is sealed in said chamber the second piston is fitted in its cylinder, a fluid sample retaining valve in the 50 lower body structure with means to open said valve for the upward flow of the well fluid, said well fluid exerting an upward pressure on the second piston, the frangible sealing means being adapted to be broken and expose the bleeding 55 duct for a bleeding discharge of the locked fluid, the pressure on the second piston forcing the first piston upwardly in its cylinder, the second piston having means to establish an upward flow of well fluid to the space surrounding the cylinder of 60 the hydraulic locked valve and thence to the 65 drill pipe. 70

12. In a device as described, a hydraulically locked valve assembly comprising in combination a tubular body structure having a chamber structure positioned therein with a first valve cylinder at the lower end thereof and a frangible sealing means with a bleeding duct at the upper end, there being a space between the body structure and the chamber structure for the upward flow of 70 fluid, a second valve cylinder connected to the body structure and positioned therebelow and means for the flow of fluid to the lower end of the second cylinder, a first piston valve in the first cylinder, a second piston valve in the second cyl- 75

inder, means connecting said piston valves, the second piston valve having a configuration at its lower end whereby when moved upwardly in the second cylinder it permits first a gradual and then an increased flow of fluid upwardly, the said chamber structure and the first cylinder being adapted to contain a locking hydraulic liquid retained between the first piston valve and the sealing means, the sealing means being adapted to be broken and thereby open the bleeding duct whereby the pressure of the fluid on the lower end of the second piston valve forces both piston valves upwardly displacing the locking liquid through the bleeding duct and thereby when the second piston valve is forced upwardly above the second cylinder, providing first for a gradual, then an increased and then a full flow of the fluid.

13. In a device as described, a hydraulically locked valve including in combination a chamber forming structure having frangible sealing means at one end, said sealing means comprising a bar-like structure with a weakened portion and a bleeding duct extending upwardly beyond the weakened structure, a movable valve means at the other end of the chamber structure, an abutment means with an inter-engaging thrust device between the valve means and the abutment means and the abutment means whereby when the chamber is filled with a locking liquid, such liquid is trapped between the valve means and the sealing means and the thrust device engaging the said abutment means, the thrust device being adapted to be subject to pressure and communicate pressure to the said valve whereby when the frangible sealing means is broken the locked liquid may discharge through the bleeding duct permitting an inward movement of the said valve means thereby disengaging the thrust device from the abutment means.

40 14. In a well tool, a well fluid sample retaining valve comprising in combination a lower tubular body structure having means for attachment to a string of drill pipe for lowering in a well and at its lower end being provided with an inlet means for well fluid, a tubular mandrel slidably and rotatably mounted in the said body structure and having a port, a first inter-engaging means between the mandrel and the body structure for lowering the body structure into a well with the body structure occupying a lowered position in regard to the mandrel, a valve forming means interconnecting between the mandrel and the inside of the body structure and having a second port positioned out of alignment with the port of the mandrel when the mandrel and body structure are being lowered in the well, the said mandrel being adapted to be lowered relative to the body structure when at the desired depth in the well to bring the said ports into alignment for upward flow of well fluid into and through the tubular mandrel, the said mandrel being adapted for partial rotation and to be moved upwardly relative to the said body and a second inter-engaging means between the mandrel and the body structure whereby on hoisting the mandrel upwardly in the well, the body structure occupies a second lowered position in reference to the mandrel with the ports out of registry, thereby retaining the sample in and above the tubular mandrel.

70 15. In a well tool, a re-circulating valve assembly including in combination a lower tubular body structure having means for inflow of well fluid at the bottom, a slidable tubular mandrel mounted therein, means for connecting the man-

drel to a string of drill pipe for lowering into the well, a well fluid sample retaining valve having an inter-acting valve means between the mandrel and the lower body for upward flow of well fluid and to retain the well fluid in the mandrel and thereabove, means for relatively moving the mandrel and the hollow body to operate said valve to its open and closed position, a re-circulating tube connected to the lower part of the mandrel and communicating with the well fluid inlet part of the body, a plug means fitted therein and having a ball with means to retain the ball and the plug from upward movement due to the pressure of the well fluid, the ball and the said plug being adapted to be forced downwardly on re-circulating slushing fluid downwardly through the tubular mandrel when the sample retaining valve is in its closed position and thereby adapted to again discharge in the well any sample retained and slushing fluid.

20 16. In a well tool, an equalizing valve assembly including in combination a lower tubular body structure having means at the bottom for inlet of well fluid, a tubular mandrel slidable in the said body, a tubular by-pass mandrel connected to the lower end of the tubular mandrel, the hollow body having a bore in which the by-pass mandrel may slide longitudinally, a by-pass port extending from the outside of the said body to the said bore and having a ball fitted therein engaging the by-pass mandrel and a plug outside of the ball with a tubular nipple outside of the plug, means to retain the lower body structure at substantially a fixed position in the well adjacent the place for obtaining a sample, an operative means for obtaining the sample and retaining a sample of the well fluid, a packing means on the body structure between the by-pass port and the intake for well fluid at the lower part of the body, the said by-pass mandrel when in its lowered position retaining the ball and plug forming a seal for the by-pass port and when in its uppermost position removing the by-pass mandrel from engagement with the ball whereby the plug and ball may be forced inwardly into the said hollow body to permit an equalizing flow of fluid between a position in the well above and below the packer.

30 17. In the art described, confining an incompressible liquid, exerting a static pressure on the confined liquid by a well fluid, the incompressibility of the liquid restraining the well fluid from flowing, releasing the liquid for slow discharge and positively forcing the discharge of the confined liquid by pressure of the well fluid and after discharge of a predetermined amount of the liquid developing a free flow of the well fluid.

40 18. In the art described in which tubing is lowered in a well to a well fluid comprising providing substantially atmospheric pressure in the tubing which is very much less than the pressure of the well fluid, confining an incompressible liquid adjacent the lower end of the tubing, exerting a static pressure on the confined liquid by the well fluid, the well fluid being prevented by the confined liquid from entering the tubing, releasing the confined liquid for a slow displacement and positively displacing a predetermined amount of liquid due to the differential pressure of the well fluid and the substantially atmospheric pressure in the tubing, the liquid being discharged into the tubing, flowing well fluid upwardly in the tubing by the action of pressure of the well formation on the well fluid.

19. In the art described in which a confined body of incompressible liquid is lowered into a well by a string of empty or substantially empty tubing, subjecting such liquid to a static pressure of a well fluid, utilizing such liquid to restrain the upward flow of the well fluid, releasing the confined liquid to the substantially atmospheric pressure in the tubing causing a positive discharge of the liquid by the greater excess pressure of the well fluid acting on the liquid, after

discharge of a predetermined quantity of liquid developing a substantially free and unobstructed flow of the well fluid into the tubing.

20. In the art described and claimed in claim 19, trapping the well fluid in the tubing to isolate the trapped fluid from the pressure in the well and elevating the trapped well fluid and the liquid to the top of the well to obtain a sample of the well fluid. 5
